UNITED STATES PATENT OFFICE.

WALTER W. DISMUKES, OF NASHVILLE, TENNESSEE, ASSIGNOR TO BRANDON PRINTING CO., OF NASHVILLE, TENNESSEE, A CORPORATION OF TENNESSEE.

FILING-CABINET.

1,303,778.

Specification of Letters Patent. Patented May 13, 1919.

Application filed June 5, 1917. Serial No. 173,006.

To all whom it may concern:

Be it known that I, WALTER W. DISMUKES, a citizen of the United States, residing at Nashville, in the county of Davidson and 5 State of Tennessee, have invented certain new and useful Improvements in Filing-Cabinets; and I do hereby declare the following to be a full, clear, and exact description of the invention, such as will enable 10 others skilled in the art to which it appertains to make and use the same.

This invention relates to filing cabinets, and more particularly to a ledger or other card tray or cabinet.

15 It is among the objects of the present invention to provide a tray or cabinet adapted to receive loose leaves or cards, such, for instance, as loose leaf ledger members, and particularly it is an object of the present invention to facilitate the posting of accounts 20 from and on the leaf sections and to facilitate the manipulation of the leaves in the tray or cabinet.

It is, therefore, a feature of my invention 25 to provide a tray or cabinet having a receiving section or box preferably with its bottom inclined so that when a number of cards or ledger leaves have been assembled in the box the top edge of each successive leaf is slightly 30 higher than the next leaf toward the rear end of the box, the bottom being inclined downwardly from the front end toward the rear end of the receiving tray.

It is another object of the present invention 35 to facilitate the posting of the books by providing for the relative offsetting of such leaves or cards as may have received entries during an interim, for instance a day, in the course of business so that when the item has 40 been entered on the ledger leaf and the latter is returned to the receiver or cabinet the card which has been itemized is placed in the cabinet in a relatively offset position to the remaining cards in the cabinet which have 45 not received an entry during the day.

It is therefore an object of the invention to provide a card or leaf tray or cabinet of such proportions and construction that the cards are adapted to be held in suitable assembled relation and may be readily and conveniently moved during manipulation by the attendant or bookkeeper, the width of

the tray providing for the relative offsetting of any or all of the cards as may be desired.

A further object of the invention is to 55 provide for the angular disposition of the stack of cards in the tray as may be most conveniently desired by the attendant or bookkeeper, and to that end a feature of the invention consists in the provision of a movable follower block provided with an adjustable back rest and which tray is also provided with an adjustable front flap or tongue coöperative with the adjustable rest on the follower block to hold the cards in a 60 desired angular position, and also to lock the cards.

A further object of the invention is to 65 provide a loose leaf or card tray or cabinet having means to accommodate the assembling in the cabinet of cards or leaves of different lengths.

Another object of the invention contemplates the provision of a loose leaf cabinet 70 or tray having a detachable and longitudinally adjustable top member capable of being lifted and pushed rearwardly along the receiving member of the tray so that it may be disposed conveniently in a position out of the way without being entirely disconnected from the receiving member or box of the tray, and which may also be dropped down over the back of the desk when this is possible by the arrangement of the cabinet 75 on the top of the desk or other support.

Another and important object of the invention is to provide a ledger leaf cabinet structure which provides for the insertion and removal of the individual ledger leaves 80 without necessitating a vertical withdrawing or inserting movement of the leaf a distance substantially equal to the total height of the card before it can be entirely removed from or inserted in the box, and to that end a feature of the invention consists in providing a cabinet having a receiving portion 85 which will hereinafter be referred to as the box with one of its longitudinal or side edges of shorter height than the opposite and parallel side.

With these and other objects in view the invention consists of the whole, the construction, and in details and combinations of the parts as will be more fully hereinafter de-

scribed, and shown in the accompanying drawings in which one embodiment of the invention is illustrated.

In the drawings:

5 Figure 1 is a perspective view from the right hand side of the device showing the cabinet as arranged on the top of a desk or support with the top of the cabinet pushed to the rear and depending behind the top 10 of the desk.

Fig. 2 is a perspective view showing the cabinet in detail with the cover pushed partly to the rear of the box.

Fig. 3 is a cross section on line 3—3 of 15 Fig. 1, and

Fig. 4 is a perspective view of the detached follower block with its adjustable back rest looking toward the rear of the block.

20 It is understood that the cabinet herein-after described may be built of any suitable material and any appropriate proportions and dimensions so as to receive various sized cards or ledger leaf sheets which it may be

25 desired to arrange within the cabinet, and in the illustrated form of the cabinet there is provided a lower portion 2 which may be termed the box in which there is adapted to be adjusted a stack or horizontal row of

30 cards or ledger leaves as may be desired, which are shown at L in Fig. 1 in dotted lines as provided adjacent one edge with a notch n for a purpose to be hereinafter described. The box section 2 is preferably

35 made of a width to receive two sizes of cards, and comprises on one side a wall 4 and on the opposite side a shorter wall 3, the front end of the box being closed as at 5 with a suitably formed upright end which in the

40 present instance is shown as provided with a curved edge 6. Longitudinally disposed within the box and extending parallel with the sides 3 and 4 is arranged a suitably shaped track or guide bar 7 having prefer-

45 ably a vertical, longitudinal edge at 8 and the opposite side of which track may be beveled as at 9. This track or guide is preferably made adjustable laterally in the box 2 by the provision of suitable means, as, for 50 instance, screws or bolts 10, one at each end, which are adapted to be adjusted in suitable apertures provided therefor in the bottom 11 of the box.

One of the important objects of the invention is to provide a cabinet for the reception of cards, loose leaves or the like, which will hold the row of cards in such relation that the successive top edges of the cards are each elevated slightly above the other 60 progressively from the rear toward the front of the cabinet, so that the attendant or bookkeeper may with rapidity and convenience "finger" or manipulate the top edges of each card in selecting cards from the group. To 65 that end the bottom 11 of the box 2 is pref-

erably given a suitable inclination, as, for instance, one inch in one foot, although this may be varied at will.

For the purpose of holding the cards or leaves securely and compactly in a stack or row when inserted in the box 2, and to prevent their curling or bending, I provide appropriate clamping means which consist in the illustrated embodiment of the invention in a front flap or presser device 12 75 which is hingedly or otherwise suitably connected, as at 12', at its lower end to the bottom 11 of the box, the flap 12 being preferably of a width substantially equal to the distance between the side wall 4 and the 80 adjacent vertical surface 8 of the guide rail 7, which is substantially equal to the width of the leaves of the smaller dimension adapted to be arranged in the box, and to support this swinging flap or presser device in the 85 desired forward or perpendicular position there is provided to bear against the front surface thereof a swinging brace 13 which is hingedly connected at one end to the rear surface of the front end 5 of the box, the 90 brace 13 being adapted to be lifted to a vertical position to permit the flap 12 to swing forwardly, and it is also capable of being swung downwardly to a horizontal position at the rear of the end 5 to press the flap 12 95 rearwardly to a vertical position, as shown in Fig. 2. Coöoperating with the front clamping device or flap 12 there is arranged and slidably mounted within the box 2 a suitable follower block indicated at 14, the 100 block having its ends extended beyond the lower portions of the walls 3 and 4 to operate in channels 15 provided therefor in the sides of the box 2 so that the follower block 14 is prevented from having vertical movement but is adapted to be shifted longitudinally of the box so that an upwardly extending back rest 16, hingedly connected at 17 at its lower end to the follower block 14, 105 may be moved to the desired position against the last of the row of leaves in the box. Different attendants or bookkeepers having charge of these devices desire to have the cards or leaves presented to them at various angles during the manipulation of the 110 leaves, and it is one of the objects of the present invention to provide for this variation of the angular presentation of the leaves in the box as the individual taste of the bookkeeper or attendant may elect, and 115 for that reason I have provided the front hingedly mounted presser flap 12 and the rear swinging back rest 16 hinged to the follower block, and in order to support the back rest 16 in any suitable angular position 120 it is provided on its rear surface, as shown in Fig. 4, with a series of lugs or shoulders 18 spaced vertically along the back rest 16 at suitable pitch from each other to receive the upper end of a latch or locking device 125 130

19 also hingedly connected to the follower block 14 so that when the follower block is moved to bring the back rest 16 to the desired position the latter may be supported 5 in angular relation to the cards or leaves as may be desired. Preferably the flap 12 is of much less length than the width of the box so as to provide a ready view of the offset cards or sheets.

10 To accommodate the arrangement of cards or leaves of different length within the box 2, the follower block 14 is shown as provided with a transverse notch or cut-away portion 14' which provides space for the 15 reception of the transversely adjustable guide track 7 which may be moved from its innermost position, as shown in Figs. 1 and 2, to a position nearer the adjacent wall 3 of the box 2. The follower block may be 20 provided with any suitable means for temporarily securing it in any desired position with relation to the box 2, and this means may comprise a suitable spring-actuated brake mechanism including blocks 25 14^a arranged in the ends of the block 14 and adapted to be sprung outwardly by springs 14^b to engage the vertical end walls of the guideways 15 in which the ends of the block 14 slide. The blocks 14^a may be retracted to 30 release the follower block 14 through means of a pair of grips illustrated at 14^c, Fig. 4.

Another feature of the invention resides in the provision of a suitable cover for the receiving section or box 2 of the cabinet, 35 this cover being illustrated at 20 and is of substantially the same proportions as the box section 2 being provided at its front end with a wall 21 having a curved edge 22 adapted to fit down over the front end 5 of the box 2 and fit the upper curved edge of 40 the latter. To facilitate the uncovering of the cards or leaves which may be contained in the box 2, and to provide for the adjustment of the cover 20 of the cabinet rearwardly with relation to the box 2 to afford 45 ready access to the cards or leaves in the box, and yet prevent the entire removal of the cover, this latter is shown as having downwardly extending bottom side flanges 50 23 to overlap the side walls 3 and 4 of the box, these side flanges being provided with longitudinally extending slots 24 to receive suitable supporting means secured on the rear end of the box 2. In this instance the 55 supports comprise rollers 25 which are mounted on bolts or other suitable supports 26 which may be mounted in rearwardly extending brackets 27 fastened to the rear end of the box 2. By this means the box cover 60 20, when it is lifted slightly at its forward end to disengage the front end of the higher wall 4 of the box, may then be moved rearwardly substantially horizontally to the desired position, or swung upwardly about the 65 supporting rollers 25 when the box cover 20

may then be dropped vertically to the position shown in Fig. 1 when the cabinet is arranged on the top of a desk or the like, which will permit the cover 20 to be lowered downwardly at the rear end of the box 2. 70 By providing the bolts 26 for supporting the rollers 25 when it is desired to entirely detach the cover 20 from the box 2 it is only necessary to remove the bolts 26 from their supporting brackets 27. 75

When the device is in use the attendant or bookkeeper may arrange the cards or leaves as indicated at L in the box 2 so that one vertical edge of the leaves rests against the higher vertical wall 4 and the lower right 80 hand corners, for instance, of the leaves rest against the adjacent vertical edge 8 of the guide bar or track 7 in which instance the notch n will be disposed within the track 7. When a card or leaf is removed for entry 85 or other purpose it may then be returned to the box 2 and the card L offset to the position shown in Fig. 1 with relation to the remaining cards in the box, in which position the notch n will straddle the guide bar or 90 track 7 and the card be held against accidental shifting movement when it is adjusted in the box, and therefore there is provided ready means for positioning certain of the cards in offset relation to the 95 cards in the box, for the ready access by the attendant, to the offset cards in the box.

What is claimed as new is:

1. A leaf or card cabinet or tray comprising a receiving section having a bottom inclining downwardly from the front end of the tray toward the rear for the purpose of presenting the top edges of the leaves successively one below the other to facilitate manipulation, and laterally adjustable means extending longitudinally of the bottom for engaging the cards. 100

2. A leaf or card cabinet having a box section with vertical side walls and a bottom elevated at its front end between the walls and extending in an inclined plane downwardly toward the rear of the box, and laterally adjustable means extending longitudinally of the bottom for engaging the cards. 110

3. A leaf or card cabinet having a box section with vertical side walls and a bottom elevated at its front end between the walls and extending in an inclined plane downwardly toward the rear of the box, and adjustable means for supporting inserted leaves 115 in upright position in the box, and laterally adjustable means extending longitudinally of the bottom for engaging the cards.

4. In a ledger leaf, or the like, cabinet, a box section, a follower block movable toward or from the front end of said section and having a tiltable back rest to engage and support the leaves at the desired position upright in the box, means for regulating the position of said rest, said block having 125 130

- a recess, and a lateral guide for a row of leaves, along which said block is adjustable, which extends through said recess.
5. In a ledger leaf, or the like, cabinet, a box section, a follower block movable toward or from the front end of said section and having a tiltable back rest to engage and support the leaves at the desired position upright in the box, means for regulating the 10 position of said rest, said block having a recess, and a lateral guide for a row of leaves, along which said block is adjustable, which extends through said recess, said guide laterally adjustable to engage rows of leaves 15 of different widths.
6. In a ledger or the like cabinet, a box section having a movable follower block with a tiltable brace, and a back plate hinged on the block and controlled by the brace, 20 and an adjustable head rest at the front end inside the box and having a brace, between which plate and rest inserted leaves may be arranged in groups.
7. In a ledger leaf or the like cabinet, a box section having a movable follower block with a tiltable plate and means on the block 25 for supporting the plate in various angles,
- an adjustable rest in the front end of the box, and means for supporting it in clamping position against a row of sheets or the like in the box.
8. In a ledger leaf or the like cabinet, a box section having a movable follower block and an adjustable rest thereon, and an adjustable head flap between which inserted 30 leaf or leaves may be arranged and secured, said rest and flap being of less width than the width of the box to permit the leaves to be readily observed when relatively offset as to the same.
9. A posting box of the character described and comprising the box proper, a hinged front plate, a hinged stop plate which in two opposite positions co-operates with said front plate to hold it vertical in the one position and tilted in the other, and a rear plate which is adjustable from front to rear and angularly adjustable, and a follower block, on which the rear plate is hinged, having an adjustable stop for the 40 plate.
- 45 In testimony whereof I affix my signature.
- 50 WALTER W. DISMUKES.
